TETRAMETHYLBENZENE PRODUCTION

David A. McCaulay, Chicago, Ill., assignor to Standard Oil Company, Chicago, Ill., a corporation of Indiana

No Drawing. Application July 26, 1955,
Serial No. 524,570

6 Claims. (Cl. 260—668)

This invention relates to the production of tetramethylbenzene by the disproportionation of trimethylbenzene.

Very recently the chemical industry has become intensely interested in tetraalkylbenzenes wherein the alkyl group is either methyl or ethyl. These tetraalkylbenzenes may be converted to various alkyl benzoic acids; particularly there is interest in the benzene nucleus containing 4 carboxylic groups. Most interest is concentrated in the tetraalkylbenzene having the durene configuration, i. e., 1,2,4,5- which leaves two unsubstituted ring positions in para orientation.

The tetramethylbenzenes are not particularly plentiful in either coal carbonization liquids or in catalytic reformate from conversion of petroleum naphthas. Furthermore, the close-boiling aromatic hydrocarbons containing a total of 10 carbon atoms make the problem of obtaining high purity tetramethylbenzenes exceedingly difficult and expensive. Catalytic reformate from the conversion of petroleum naphtha does contain quite large amounts of benzenes containing a total of 9 carbon atoms, primarily trimethylbenzenes and ethyltoluenes. It is possible by fractional distillation to obtain a fraction consisting essentially of about 90 mole percent trimethylbenzenes and not more than about 10 mole percent of ethyltoluene; with some loss in yield of trimethylbenzene, it is feasible to reduce the ethyltoluene content to on the order of 5%. It is known that trimethylbenzenes can be converted to tetramethylbenzenes and xylene utilizing various acid-type catalysts. For example, HF-BF₃ catalyst readily converts trimethylbenzenes to tetramethylbenzenes, but the isodurene isomer is the predominant member and, under some conditions, essentially the only component of the tetramethylbenzene product. Other acid catalysts tend to produce a mixture of tetramethylbenzenes wherein isodurene is predominant.

An object of this invention is the production of tetramethylbenzene, particularly a mixture of tetramethylbenzenes wherein durene is the predominant component. Another object of the invention is a more economical process for disproportionating trimethylbenzenes to a mixture of tetramethylbenzenes. Yet another object is a process for utilizing a mixture of C₉ aromatic hydrocarbons containing some ethyltoluene and the remainder trimethylbenzene in high yield to tetraalkylbenzenes. A further object is a process for disproportionating trimethylbenzenes wherein the by-product xylene fraction is of superior economic value. A particular object is an economic disproportionation process for converting trimethylbenzenes to tetramethylbenzenes utilizing liquid HF as the catalyst. Other objects will become apparent in the course of the detailed description.

In the process of this invention, a trimethylbenzene or a mixture of trimethylbenzene isomers is contacted with between 25 and 100 volume percent of liquid HF catalyst; the contacting is carried out at a temperature between about 80° C. and 190° C. for a time sufficient to produce an appreciable amount of tetramethylbenzene and by-product xylene. In general, the higher the tempera-

2

ture, the shorter the contacting times used. The HF is separated from the product hydrocarbon mixture and the desired tetramethylbenzene fraction is recovered from said mixture.

5 The hydrocarbon feed to the process may consist entirely of trimethylbenzene, either a single isomer or a mixture of two or all of the isomers. The isomeric trimethylbenzenes are hemimellitene (1,2,3-trimethylbenzene), pseudo cumene (1,2,4-trimethylbenzene), and 10 mesitylene (1,3,5-trimethylbenzene). Or the hydrocarbon feed may consist of one or more trimethylbenzene isomers and one or more ethyltoluene isomers; as much as 10 mole percent of ethyltoluene may be present in the feed without any appreciable adverse effect on the yield 15 of tetramethylbenzenes. It is preferred to have not more than about 5 mole percent of ethyltoluene present. In addition to the trimethylbenzene and ethyltoluene, the feed may contain a small amount of close-boiling non-aromatic hydrocarbons. The presence of non-aromatic hydrocarbons introduces a complication in the purity of the product and also cracking reactions are introduced at the higher temperatures of operation. Some of the cracked non-aromatic hydrocarbons alkylate the benzene hydrocarbons with a consequent loss of benzene hydrocarbons to undesired by-products. A suitable source of trimethylbenzene feed is the C₉ fraction obtained by extractive distillation of a catalytic reformate fraction; this extracted aromatic-rich C₉ fraction which contains on the order of not more than 5 volume percent of non-aromatic hydrocarbons is fractionally distilled to eliminate 20 substantially all of the C₉ aromatic hydrocarbons which do not boil closely about the trimethylbenzene range. A trimethylbenzene concentrate containing 10 mole percent of ethyltoluenes and some non-aromatic hydrocarbons is 25 readily obtained. By careful distillation it is possible to reduce the ethyltoluene content of the concentrate to about 5 mole percent. A particularly suitable feed for the process is obtainable from the C₉ aromatic hydrocarbon fraction produced by glycolic solvent extraction of 30 catalytic reformate; this fraction contains essentially to no non-aromatic hydrocarbon component; thus it is possible to produce by fractional distillation a concentrate containing between about 5 and 10 mole percent of ethyltoluenes and the remainder essentially only trimethylbenzenes. A source of essentially pure trimethylbenzenes is the product from the disproportionation of xylenes using liquid HF catalyst and particularly liquid HF-BF₃ catalyst.

35 The catalyst utilized in the process of this invention is substantially anhydrous hydrofluoric acid or even liquid hydrogen fluoride. In order to maintain catalyst activity at very high levels, the liquid HF should not contain more than about 2 or 3 weight percent of water. In order to maintain the water content of the system at a low level, 40 the entire process is carried out under substantially anhydrous conditions, i. e., the feed hydrocarbons themselves must be of low water content in order to avoid introducing deleterious amounts of water into the system.

45 It has been found that the trimethylbenzenes disproportionate very readily when utilizing substantially anhydrous liquid HF catalyst. The rate of conversion is so great that it is not necessary to use very large amounts of catalyst. Appreciable conversion can be obtained with rather small amounts of catalyst. Furthermore, it is not necessary to use more than 100 volume percent of liquid HF catalyst based on feed hydrocarbons. In general, the catalyst usage will lie between 25 volume and 100 volume percent based on feed hydrocarbons. It is preferred to operate with between about 50 and 80 50 volume percent of catalyst.

55 The disproportionation process is carried out at a temperature within the range of about 80° C. and 190° C.

Temperatures below about 80° C. need prohibitively long times for reasonable yields of tetramethylbenzenes. While very short times are obtainable at temperatures of 190° C. and even higher, cracking reactions come into play, particularly when ethyl groups are present in the feed. The best balance of contacting time, catalyst usage, and side reactions is obtained in the temperature range of about 130° C. and about 170° C.

The disproportionation reaction approaches an equilibrium condition at which about one-half of the trimethylbenzenes charged have been converted to tetramethylbenzenes and xylene. Thus the time for which the contacting of feed and catalyst must be carried on is dependent upon the degree of conversion of the trimethylbenzenes desired as well as on the temperature of contacting and the amount of catalyst used. The rate of conversion decreases very rapidly after about the 30% conversion point has been reached and it is considered that for normal purposes the process will be carried out while maintaining the degree of conversion between about 20% and 30% of the trimethylbenzenes charged. At constant conversion, the contacting time is dependent upon the temperature of operation and also on the amount of catalyst used. Broadly, the lower the temperature, the longer the corresponding time at fixed catalyst usage. And the lower the catalyst usage, the longer the corresponding time at a fixed temperature. When operating with the preferred catalyst usage of between about 50 and 80 volume percent at the preferred temperature of between about 130° C. and 170° C. and at a trimethylbenzene conversion between about 20 and 30 mole percent, the time of contacting is between about 3 minutes and about 60 minutes, the lower times corresponding to the higher temperatures.

Based on experimental data, the relationship between temperature, catalyst usage and time to reach conversion of about 25% and 44% have been calculated. This relationship is set out in Table I. The flexibility of the process is clearly shown by the information set out in Table I. Thus the throughput for a given piece of equipment may be radically changed by a small change in temperature, or the degree of conversion may be controlled very accurately at a given temperature by changing the amount of catalyst used.

TABLE I

° C.	Minutes for 25% Conversion		Minutes for 44% Conversion	
	HF, Vol. percent on Feed		HF, Vol. percent on Feed	
	50	100	50	100
100	640	320		
130	60	30	240	120
150	16	8	64	32
170	4	2	16	8
180	2	1	8	4

It is to be understood that the process of this invention is a liquid phase reaction and sufficient pressure must be maintained on the system in order to keep both the feed hydrocarbons and the HF catalyst in the liquid state.

The tetramethylbenzenes consist of prehnitene (1,2,3,4-tetramethylbenzene), isodurene (1,2,3,5-tetramethylbenzene) and durene (1,2,4,5-tetramethylbenzene). The apparent equilibrium composition contains 50% of isodurene, 45% of durene and 5% of prehnitene. However, when operating with pseudo cumene feed or the equilibrium mixture of trimethylbenzene in which pseudo cumene is the predominant component, the composition of the tetramethylbenzene product does not immediately

reach the equilibrium composition. The durene isomer appears to be the predominant product of the disproportionation and isodurene appears to be formed by isomerization of durene. By limiting the degree of conversion to between about 20% and 30%, it is possible to produce a tetramethylbenzene product fraction where durene is the predominant component. Since durene is the preferred commercial tetramethylbenzene, this is a result most eminently desired.

A further interesting feature of the process is in the composition of the xylenes which are produced in the disproportionation reaction. At low conversions of trimethylbenzene the xylenes produced consist entirely of about equal amounts of the ortho and meta isomers. No para-xylene appears to be formed. However, as the degree of conversion of trimethylbenzene increases, para-xylene appears in the xylene fraction and eventually the equilibrium mixture appears consisting of about 60% of meta, 25% of ortho, and 15% of para. Since high purity ortho-xylene and meta-xylene may be readily fractionated from a mixture containing only these isomers, it is desirable to control the degree of conversion of the trimethylbenzene to avoid the formation of para-xylene whose presence complicates this separation. By operation in the preferred region of 20% to 30% conversion a xylene by-product fraction containing essentially no para-xylene is obtainable.

Durene which has a melting point of about 80° C. is very readily separated by fractional crystallization from the isodurene and prehnitene isomers which melt respectively at -24° C. and -6° C. Thus by a very simple conventional fractional crystallization procedure it is possible to separate essentially pure durene from the tetramethylbenzene product of this process. Since isodurene and prehnitene have a boiling point difference of about 7° C., high purity prehnitene may be readily produced by fractional distillation of the mother liquor from the fractional crystallization procedure.

When ethyltoluene is present in the feed to the process, ethyltrimethylbenzenes are formed in addition to the tetramethylbenzenes. The ethyltrimethylbenzenes can be separated by fractional distillation from the tetramethylbenzenes. When a raw material is desired for the production of polycarboxylic aromatic acids, the tetramethylbenzenes and the ethyltrimethylbenzenes can be charged to the oxidation process to produce a mixture of tetracarboxylic acids. The presence and location of the ethyl group will not affect the composition of the tetracarboxylic acids. The various isomers of the acids may be separated by well known techniques. The presence of small amounts of the ethyltoluene will have no deleterious effect on the process.

The results obtainable by the process of the invention are set out in many illustrative examples. The tests were carried out in a one-liter Hastelloy autoclave provided with a motor-driven stirrer. In the experimental procedure, the feed hydrocarbon was charged to the autoclave and the whole heated to about 30° C. above the desired reaction temperature. The liquid HF catalyst (commercial anhydrous hydrofluoric acid containing 99.5% HF) was then charged to the autoclave; the desired reaction temperature was thereby reached within a few seconds. The mixture was stirred for the desired time and at the end of this time the entire mixture was withdrawn into a polyethylene flask immersed in a Dry-Ice acetone bath. About one volume of cold water per volume of liquid HF charged was added to the flask. The upper layer of hydrocarbons was separated from the lower aqueous layer. The hydrocarbon layer was neutralized and fractionated through a distillation column providing about 30 theoretical plates. The close-boiling fractions were analyzed by infrared absorption techniques for individual isomer content.

The pseudo cumene utilized was 99.4% pure. The

other hydrocarbons were purchased from the Eastman Kodak Company and were white label grade.

Example A

In this example, three tests were carried out utilizing a mixture of trimethylbenzenes as the feed hydrocarbon. In Test No. 1, some indane impurity was also present. The results of this example are set out in Table II. Test No. 3 shows that at 100° C. and 120 minutes time only 10% of the feed was converted. Test No. 2 shows that at 165° C. and only 5 minutes time 28% of the feed was converted. Test No. 1 shows that at 135° C. and a time of 240 minutes about one-half of the trimethylbenzenes were converted. This test shows that some reaction took place between indanes and the trimethylbenzenes.

Example B

In this example, a series of tests were carried out utilizing pseudo cumene (99.4% purity) as the sole feed component. The results of this series of tests are set out in Table III. Tests 4 through 7 show the effect of HF catalyst usage on the degree of conversion of the pseudo cumene. Thus at constant temperature of 100° C. and constant time of 60 minutes, changing the HF usage from 25% to 60% resulted in an increase in conversion from 6% to 15%. A further increase to 100 volume percent of catalyst resulted in a conversion of 18%. Under these conditions, only 28% was converted when the catalyst usage was increased to 212%. These four runs show that there is no real economic incentive to operating at above 100 volume percent of liquid HF catalyst.

Test No. 6 shows that at 18% conversion, durene formed 55 mole percent of the tetramethylbenzene fraction, whereas Test No. 7 shows that durene had decreased to 49% of the tetramethylbenzene product when the conversion had increased to 28%.

Tests 9 through 11 were carried out at 165° C. and 100 volume percent of liquid HF catalyst and show the effect of time on the process. At three minutes time (Test No. 11) 30% of the pseudo cumene was converted; at 10 minutes time (Test No. 10) 36% was converted, and Test No. 9 indicates that 240 minutes is too long since only 50% was converted despite this very much longer contacting time. The product tetramethylbenzene composition shows the importance of degree of conversion on the amount of durene present. At this very high temperature, even at 3 minutes' time, the tetramethylbenzene fraction contained only 50 mole percent of durene. In 10 minutes, the durene and isodurene amounts had reversed and isodurene was predominant. Test No. 9 indicates that the equilibrium composition is about: Isodurene, 50%, durene, 45%, and prehnitene, 5%, since it is the same as that obtained in Test No. 10.

The composition of the product trimethylbenzene fraction is of interest in that the data show that pseudo cumene is not only disproportionated but is also isomerized. Test No. 6 shows that 15% of the unconverted pseudo cumene had been isomerized to mesitylene and hemimellitene. Runs 8 through 11 indicate that an equilibrium condition is reached wherein the product trimethylbenzene fraction consists of pseudo cumene, 65%, mesitylene, 30%, and hemimellitene, 5%.

Tests 6, 8, and 9 show the product xylene compositions. In Test 6 where only 18% of trimethylbenzene charged was converted the product xylenes consisted of equal molar amounts of ortho-xylene and meta-xylene. In Test No. 8, where 38% of the pseudo cumene charged was converted the product xylenes showed that about one-fifth of the ortho-xylene had been converted to para-xylene. Test No. 9 indicates that eventually an equilibrium condition will be reached corresponding to the published equilibrium compositions of the three xylene isomers, i. e., meta-xylene, 60%, ortho-xylene, 25%, and para-xylene, 15%.

Example C

In this example, the extent of possible conversion of trimethylbenzenes and the equilibrium distribution of tetramethylbenzene isomers was studied. The tests were carried out at 100 volume percent of liquid HF based on feed and a temperature of 165° C. In Test 13, pseudo cumene alone was contacted for 240 minutes. In Test No. 14, a mixture consisting of 45% of isodurene and 55% of mixed xylenes was contacted for 50 minutes. In Test No. 15, about an equal molar mixture of durene, pseudo cumene and xylene was contacted for 8 minutes. In Test No. 16, a mixture of durene, 25%, pseudo cumene, 50%, and xylene 25%, was contacted for 8 minutes.

The results of these tests are set out in Table IV.

¹ Tar and gas also formed.

Test No. 16 shows that the presence of durene in the feed does not have any effect on the distribution of the tetramethylbenzene product. At this short time of contacting, it appears that no prehnitene was formed. However, the durene and isodurene ratios closely approached those obtained in Test No. 13 when pseudo cumene alone was the feed.

Test No. 16 also indicates that the presence of xylene and durene in the feed had no effect on the isomerization of the pseudo cumene to the mesitylene and hemimellitene isomers, as evidenced by the distribution in Test No. 13. Test No. 14, when compared with Test No. 13, indicates that isodurene and xylene interact under these conditions to produce an equilibrium mixture of xylene, trimethylbenzene, tetramethylbenzene and some pentamethylbenzene. In both Tests 13 and 14, about one-half of the hydrocarbon product consists of trimethylbenzene, even though in one test only trimethylbenzene was charged and in the other no trimethylbenzene was charged. In Test No. 15, the results show that a system containing xylene, trimethylbenzene and tetramethylbenzene will adjust itself to what appears to be the equilibrium distribution of the three polyalkylbenzene materials. Thus in Test No. 5, the product contained very close to the same distribution as that in Tests 13 and 14 where entirely different feeds were charged. In Test No. 16, the supposition that the product distribution had an equilibrium content of about 25 mole percent of xylene, 50 mole percent of trimethylbenzene and 25 mole percent of tetramethylbenzene was tested. Within the error of the determination, the product hydrocarbons had the same polyalkylbenzene distribution as the feed. The evidence that, under these conditions, reactions took place is present in the isomerization of pseudo cumene to a mixture of trimethylbenzenes and of the durene to a mixture of durene and isodurene. Thus, based on the data presented in Table IV, it appears that any process for the production of tetramethylbenzene by the HF-catalyzed conversion of trimethylbenzenes must consider itself limited to about 50% conversion per pass.

Example D

In this example, the effect of ethyltoluene in the feed to the process was examined. In Test No. 17, a mixture of pseudo cumene, mesitylene and hemimellitene as the trimethylbenzene component, 90%, and ethyltoluene, 10%, was contacted at 135° C. for 240 minutes with 120 volume percent of liquid HF catalyst. The results of this test are set out in Table V as well as the results of Test No. 8. Test No. 17 shows that ethyltoluene did interact with trimethylbenzene to form ethyltrimethylbenzene and toluene. Approximately 90% of the ethyltoluene disappeared. Tests 8 and 17 show that, if anything, the presence of ethyltoluene has a slight effect in

decreasing the amount of trimethylbenzene converted to tetramethylbenzene but this effect is countered by the production of ethyltrimethylbenzene so that the tetramethylbenzene production is very close to the same when the feed is trimethylbenzene alone or a mixture of trimethylbenzene and ethyltoluene.

In the examples, the hydrocarbons have been separated from the HF catalyst by quenching the system with cold water. Since this procedure produces a dilute acid which is of no value for reuse without reprocessing, it is primarily a laboratory technique. At about 100° C. the trimethylbenzenes are soluble in liquid HF to the extent of about 15 volume percent so that 2 phases always exist in the contacting zone. The hydrocarbon phase may be separated from the acid phase by decantation or other physical separation means. When the conversion is being carried out so that the equilibrium mixture of tetramethylbenzenes is the product, the separated acid phase containing dissolved hydrocarbons may be recycled directly to the contacting zone. When it is desired to operate under conditions such that recycle of dissolved hydrocarbons is undesirable, the HF may be recovered in a substantially pure form by distilling or flashing the HF away from the higher boiling dissolved hydrocarbons. Owing to the very low boiling point of liquid HF, this separation may be carried out under pressure without cooling the liquid HF too greatly.

The above show that it is possible to produce a durene-rich tetramethylbenzene fraction in good yield in an economic process involving relatively cheap liquid HF catalyst in relatively small amounts and at commercially feasible temperatures and times of contacting. Furthermore, they show that the process is applicable to trimethylbenzene feeds such as are readily obtainable from the petroleum industry.

Thus having described the invention, what is claimed is:

1. A process for the production of durene comprising (A) contacting, under substantially anhydrous conditions, a feed comprising essentially at least one trimethylbenzene, with liquid HF catalyst, in an amount between 25 and 100 volume percent on feed, at a temperature between about 130° C. and 170° C., for a time such that between 20 and 45 mole percent of said trimethylbenzene is converted, said time being between about 2 minutes and 240 minutes, the higher temperatures and higher catalyst usage corresponding to the shorter times, (B) removing catalyst from a product hydrocarbon mixture comprising xylene, trimethylbenzene and tetramethylbenzene, (C) separating the tetramethylbenzene product, wherein durene is the predominant isomer, and (D) crystallizing essentially pure durene from said tetramethylbenzene product.

2. The process of claim 1 wherein said feed contains not more than about 10 mole percent of ethyltoluene.

3. The process of claim 1 wherein said catalyst usage is between about 50 and 80 volume percent.

4. The process of claim 3 wherein the temperature is between about 130° C. and 170° C., the mole percent of trimethylbenzene converted is between about 20 and 30, and the time is between about 3 minutes and 60 minutes, the lower times corresponding to the higher temperatures.

5. The process of claim 1 wherein the durene-poor tetramethylbenzene fraction is cycled to the trimethylbenzene contacting step A.

6. The process of claim 1 wherein the feed is a close-boiling mixture of C₉ aromatic hydrocarbons consisting essentially of pseudo-cumene, mesitylene, hemimellitene, and not more than about 10 mole percent ethyltoluenes.
